US00D937338S

(12) **United States Design Patent** (10) Patent No.: **US D937,338 S**
(45) Date of Patent: **** Nov. 30, 2021**

(54) **DIGITAL MICROSCOPE**

(71) Applicant: **Xiaorong Luo**, Laohekou (CN)

(72) Inventor: **Xiaorong Luo**, Laohekou (CN)

(**) Term: **15 Years**

(21) Appl. No.: **29/773,202**

(22) Filed: **Mar. 8, 2021**

(51) LOC (13) Cl. **16-06**

(52) U.S. Cl.

USPC **D16/131**

(58) **Field of Classification Search**

USPC D16/130-136

CPC G02B 23/16

See application file for complete search history.
